(57) **CLAIM**

The ornamental design for a mirrored door system, as shown and described.

DESCRIPTION

FIG. 1 is a front elevation view of a mirrored door system having my new design with the doors in an open position; FIG. 2 is a top plan view thereof;

FIG. 3 is a rear elevation view thereof;

FIG. 4 is a bottom plan view thereof;

FIG. 5 is a right side view thereof, the opposite being a mirror image; and,

FIG. 6 is a front elevation view showing the doors in a closed position.
